RIB ATTACHMENT FOR METAL LATH

William G. Hurlbert, Jr., Niles, Ohio, assignor to
The Bostwick Steel Lath Company, Niles, Ohio,
a corporation of Ohio

Application August 17, 1936, Serial No. 96,489

2 Claims. (Cl. 72—117)

This invention relates to an improved attachment for increasing the stiffness of metal lath during handling or installation and which also serves as ultimate reinforcement when the lath is embedded in the finished wall.

It is acknowledged that various types of lath for forming a permanent plaster base have been formed with integral upstanding ribs, and also that heretofore it has been proposed to place 10 separate reinforcing ribs on previously formed lath. However, in the latter case, the separate ribs are usually intended for use with a particular type of lath and are also open to the objection that the method of attachment is more or 15 less tedious in the respect that the rib must be clinched to the lath at various places by manual labor if the attachment is made on the job, or, on the other hand the connection must be effected by special machinery at the shop.

Accordingly, a primary object of the invention 20 is to remedy the objections above referred to and provide an attachment which is of more or less universal application, both with respect to the type of lath and the point of application thereto without special apparatus at the factory or the place of installation.

Another and more specific object of the invention is to provide an attachment in the form of a rib which may be fitted to various types of lath, 30 such, for example, as the slotted sheet type or the expanded diamond mesh type, after manufacture, by the simple act of applying the same to the lath surface and driving the same with a hammer or maul in the direction of its length so that 35 offset engaging members will become simultaneously and firmly wedged over the strips or strands which lie between or form the openings.

A further object of the invention is to provide 40 a strong and yet comparatively light-weight rib which enables the relatively inexpensive plain type of lath to be converted into the rib type at such slightly additional cost that, in competition with lath having preformed ribs, the price favors the plain lath equipped with the present invention. Moreover, the ribs can be of any desired 45 depth and may be spaced close together or far apart according to the width of the span, thereby imparting any desired stiffness to pre-fabricated metal lath of any type for meeting a wide range of specifications.

With the above and other objects in view which 50 will more readily appear as the nature of the invention is understood, the invention consists 55 in the novel construction, combination, and ar-

angement of parts hereinafter more fully described, illustrated and claimed.

A preferred and practical embodiment is shown in the accompanying drawing in which:—

Fig. 1 is a perspective view of a portion of rib attachment constructed in accordance with the present invention.

Fig. 2 is a plan view of a portion of one type of lath having the present rib applied thereto.

Fig. 3 is a longitudinal sectional view taken on the line 3—3 of Fig. 2.

Fig. 4 is a detail cross-sectional view taken on the line 4—4 of Fig. 2.

Fig. 5 is a plan view of another type of lath having the present attachment applied thereto.

Fig. 6 is a detail cross-sectional view taken on the line 6—6 of Fig. 5.

Fig. 7 is a diagrammatic perspective view on a reduced scale illustrating the application of the invention to the type of lath shown in Fig. 5.

Similar reference characters designate corresponding parts throughout several figures of the drawing.

As will be observed from Fig. 1 the present attachment is designated generally as A, and includes a transversely arched body having the wings 1 and 2 and whose lower edges 3 are provided at suitable spaced locations with lath engaging members 4. These members are preferably arranged in opposite pairs and project downwardly from the bottom edges 3 of each of the wings so that when the attachment is applied to the lath the bottom edges 3 engage one side of the lath while the members 4 project through openings formed in the lath.

Although the members 4 are shown as arranged in opposite pairs, nevertheless, it is within the scope of the invention, if desired, to make them in staggered relation on the bottom edges of opposite wings. Also it will be understood that the rib constituting the body of the attachment may be of any depth according to the type of lath with which the rib is intended to be used.

The lath engaging members 4 are preferably of hook formation and include an arm portion 4a offset from the lower edge 3 of the rib and the forwardly extending arm 4b which lies substantially parallel with the edge 3 from which it is offset to provide the space or bight 5. The edge of the arm 4b nearest the edge 3 of the rib may 50 be inclined as indicated at 4c to produce a wedging effect between the arms 4b and the edge 3 of the rib.

In practice the rib attachment A with the hook type of lath attaching members 4, may be 55

laid upon the type of lath L shown in Fig. 2, so that the elements 4 register with openings a therein as will be apparent from the dotted line position of the rib shown in Fig. 3. When thus 5 positioned the rib may be struck on one end with a hammer or maul thereby driving the entire rib counter to the direction of the arms 4b and 10 openings 5 of the members 4 to straddle and wedgingly engage the portions b of the lath adjacent the openings. When thus applied the 15 rib becomes firmly interlocked with the body of the lath and the latter is ready for use. If desired, any one of the arms 4 may be struck with a hammer so as to be deformed upwardly and 20 thus clinch or lock the entire rib in position on the lath. However, it is to be understood that this is simply an alternative possibility because the intended arrangement and construction is such that the rib may be applied and attached 25 to the lath by force applied to one end of the rib to cause the latter to move parallel with the general plane of the body of the lath, thus greatly simplifying the method of attachment.

Referring to Fig. 5 which shows the diamond 25 mesh or expanded type of lath L, it will be apparent that the present attachment may be applied in the same manner as in the case of the lath L. From Fig. 6 it will be observed that the hook elements 4 straddle the connecting points of 30 the strands s of the lath to unite the rib to the lath and holding it in position.

Fig. 7 is intended diagrammatically to indicate, 35 on a reduced scale, a section of expanded metal lath with the rib applied thereto so that it will be clearly understood that the rib attachment A may be of any length desired. The rib is preferably made in length corresponding to the overall length of the lath so as to constitute complete reinforcement throughout. Also, it will be 40 understood that a plurality of ribs may be attached to the lath in parallel relation where the nature of the installation requires additional reinforcement.

From the foregoing it will be apparent that the 45 distinctive feature of the present invention resides in the provision of a rib which may be attached to any previously manufactured lath, regardless of its particular type thereby to provide lath

manufactured without ribs with any selected number of ribs according to immediate specifications. Moreover, a distinctive feature resides in the provision of a rib which may be attached by force applied to one end of the rib which will 5 drive it in the direction of its length to effect attachment.

Without further description it is thought that the features and advantages of the invention may be readily understood and also that changes 10 may be resorted to within the scope of the appended claims without departing from the spirit of the invention.

I claim:

1. An attachable and detachable stiffening rib 15 for expanded metal lath, said rib including a wall of sheet metal to be seated at one edge against one face of the metal lath and to have a substantially perpendicular relationship to the lath when applied thereto, hook members formed as 20 integral portions of said wall, said hook members extending from said edge of said wall at spaced intervals therealong and being disposed in the plane of said wall, each hook member including a portion spaced from said edge of said wall and 25 a portion joining one end of said spaced portion to said wall, said portions being of a depth and length, respectively, effectively to prevent bending of the hook members in their planes, the first mentioned portion of each hook member cooperating 30 with said edge of said wall to define a wedge-shaped slot diminishing in depth from its open end, said rib thus being adapted to be seated at its said edge against a face of a sheet of expanded metal lath with its hook formations extending through voids in the lath and with the open ends of its slots aligned with web portions of the lath and to be then driven longitudinally relative to the lath to effect its firm attachment thereto by the wedging cooperation 35 with said webs of the edges defining said slots.

2. An attachable and detachable stiffening rib 40 for expanded metal lath, said rib being of arched cross section and including a pair of spaced apart side walls each having hook members and slots 45 as set forth in claim 1.

WILLIAM G. HURLBERT, JR.
